UNITED STATES PATENT OFFICE.

DANIEL PYZEL, OF SAN FRANCISCO, CALIFORNIA.

DEPHLEGMATOR AND RECTIFYING-COLUMN.

1,276,690.

Specification of Letters Patent. Patented Aug. 20, 1918.

Application filed October 10, 1916. Serial No. 124,912.

To all whom it may concern:

Be it known that I, DANIEL PYZEL, a subject of the Queen of Holland, residing in the city and county of San Francisco, State of California, have invented a new and useful Dephlegmator and Rectifying-Column, of which the following is a specification.

My invention relates to the art of distilling, and the principal object of the invention is to provide means for condensing and removing liquids of definite boiling points from saturated vapors containing liquids of different boiling points.

My invention is especially adapted for use in the art of refining petroleum oils. In that art an oil which is a complex mixture of liquids of different boiling points is heated to produce a vapor which is in turn a complex mixture of vapors of different boiling and condensing points. One of the principal objects of distilling petroleum oils is to separate the complex liquid into a number of different liquids, each of which has a more or less definite boiling point, and my invention is especially designed and used for this purpose. This I accomplish in the petroleum distilling art by passing the vapors through a series of dephlegmators, each of which is similar to that described herein, the vapors being successively cooled to lower temperatures in their passage through these dephlegmators, and liquids having successively lower boiling points being extracted from the vapors in successive dephlegmators.

Further objects and advantages will be made evident hereinafter.

Referring to the drawing, which illustrates one of the dephlegmators:

Figure 1 is a vertical cross section. Fig. 2 is a section on the plane 2-2 of Fig. 1, this plane being viewed in the direction of the arrow.

Fig. 3 is a section on the plane 3-3 of Fig. 1, this plane being viewed in the direction of the arrows.

In the form of the invention illustrated in the drawing, a shell 11 is provided with a vapor inlet 12 in the side thereof, near the bottom, and a vapor outlet 13 is provided in the side thereof, near the top. A tight cover 14 is secured in place on the shell 11 by means of bolts 15, and a cooling coil 16 is suspended from this cover, this cooling coil being provided with a water inlet pipe 17 and a water outlet pipe 18 through which the cooling water is supplied and removed.

In some cases I prefer to use residuum or distillate as a cooling medium. Surrounding the coil 16, and suspended from the underside of the cover, is a deflector plate 19, this deflector plate extending down to a point somewhat below the coil 16 and below the vapor outlet 13.

A pair of angle irons 20 are secured inside the shell 11 extending across the bottom thereof.

Located inside the shell 11 are a series of alternate circular pans 21 and annular pans 22, the circular pans being considerably smaller in diameter than the shell 11, and the annular pans being of the same diameter as the interior of the shell and having central openings 23 which are somewhat smaller in diameter than the circular pans 21. The pans 21 and 22 are supported on bolts 24 and are suitably spaced by pipe spacing members 25. The three lower pans 26 are hereinafter called the redistilling pans and are located below the vapor inlet 12 and therefore out of the path of the vapor. The remainder of the pans 27 are located between the vapor inlet 12 and the vapor outlet 13, and are hereinafter called the condensing pans, the hot vapors following the path of the arrows through the openings 23 in the pans 22 and around the outer edges of the circular pans 21. The top pan 28 which is of annular form is provided with a central pipe 29 which extends up inside the coil 16 to a point very near the cover 14. All the pans 21 and 22 and the pipe 29 are assembled as a whole and rest on the angle iron members 20. The cover 14, with its coil, can be removed as a unit, and the pans 21 and 22 can then be lifted out as a unit, thus providing for great ease of repair.

The shell 11 is closed by a bottom 30, and a steam coil 31 is placed in the lower portion of the shell 11 close to the bottom 30, this steam coil 31 being supplied with steam through a pipe 32 and having the general form shown in Fig. 3. Small perforations 33 are formed in the upper surface of the pipe through which steam may be injected into the interior of the shell. An outlet pipe 34 is secured in the bottom 30, this outlet pipe being surrounded by a deflector 35 having small slots 36 therein.

In practice, a number of dephlegmators, such as that illustrated, are used, being connected in a series through which the vapor is successively passed, each dephlegmator

delivering a product having a particular boiling point.

The method of operation is as follows:

Vapor is admitted to the vapor inlet 12, passing upwardly through the interior of the shell 11, passing through the opening 23 in the center of pans 22, and around the outer edges of the pans 21. Small openings 40 are provided on the inner edge of the pans 22 next to the opening 23, and similar openings 41 are provided near the outer edges of the pans 21, the openings 40 being so located that any liquid falling therethrough falls on one of the pans 21 directly below, and any liquid from the opening 41 falls on the pan 22 below. The vapors, after passing between and around the various pans 21 and 22, are delivered by the pipe 29 to the extreme top of the shell 11, and pass downwardly between the pipe 29 and the deflector plate 19, passing in and around the water cooling coil 16. A condensation therefore takes place around this coil, the condensed liquid dropping from the cooling coil 16 onto the upper pan 28. This liquid then passes successively to the various pans 21 and 22 through the openings 40 and 41, being finally delivered from the last of the condensing pans 27 onto the first of the redistilling pans 26. The hot vapor in its passage over the pans 21 and 22 tends to evaporate from the pans any liquid having a substantially lower boiling point than the temperature of the vapors, and in the same way the liquid in the pans and in the falling streams from the openings 40 and 41, through which the vapor passes, tends to collect from the vapor any small particles of liquid which are carried in the vapors, 40 this liquid, of course, being of a higher boiling point than the temperature of the vapors. As a result, the liquid in the last of the pans 27 has a boiling point which is very close to that of the entering vapors but 45 slightly below that point due to the presence of the coil 16 in the top thereof. The liquid from the last of the condensing pans 27 falls into the first of the redistilling pans 26. These redistilling pans are not subjected to 50 the action of the vapor, but may be subjected to the action of steam from the steam coil 31. A redistillation therefore takes place in these pans and the character of the final product which is delivered to the pipe 34 may therefore be varied by regulating the 55 flow of steam delivered through the pipe 32.

In the practical operation of the invention, the refiner tests the character of the

distillate delivered from the pipe 34, and if he finds that the distillate delivered is of 60 too low a boiling point he increases the flow of steam through the pipe 32, so that the distillates of lower boiling point are re-evaporated in the redistilling pans 26, and the resulting product delivered to the pipe 34 is 65 somewhat reduced in amount and raised in boiling point. The use of the redistilling pans 26 is important, as it is difficult to proportion an apparatus of this character to give a distillate of a certain boiling point 70 unless these pans are used. By the use of these pans the refiner is able to separate the various products with great accuracy, and he is able by a suitable manipulation of the steam supply to maintain these products 75 constant even where the temperatures and constituents of the vapors delivered to the inlet 12 vary within considerable limits.

I claim as my invention:—

1. In a dephlegmator, a shell, means for 30 supplying vapors to the bottom of said shell, means for withdrawing vapors from the top of said shell, an artificial cooling coil located in the path of said vapors in the top of said shell, a rectifying column so located as to 35 receive and redistill the condensate from said artificial cooling coil, said redistillation being accomplished by the hot vapors passing through said shell around said rectifying column, redistilling means in the bottom of 40 said shell so located as to receive the condensate from said rectifying column, and auxiliary heating means for the bottom of said shell.

2. In a dephlegmator, a shell, means for 45 supplying vapors to the bottom of said shell, means for withdrawing vapors from the top of said shell, an artificial cooling coil located in the path of said vapors in the top of said shell, a rectifying column so located as to 50 receive and redistill the condensate from said artificial cooling coil, said redistillation being accomplished by the hot vapors passing through said shell around said rectifying column, redistilling means in the bottom of 55 said shell so located as to receive the condensate from said rectifying column, auxiliary heating means at the bottom of said shell, and means to regulate the amount of 60 said heat so supplied.

In testimony whereof, I have hereunto set my hand at the city and county of New York, State of New York, this 29th day of September, 1916.

DANIEL PYREN.
